US00D642611S

(12) **United States Design Patent**
Clegg et al.

(10) **Patent No.:** US D642,611 S
(45) **Date of Patent:** ** Aug. 2, 2011

(54) **VIDEO BOOK**

(75) Inventors: **Timothy P. Clegg**, Manhattan Beach, CA (US); **Michael D. Ronk**, Lawndale, CA (US)

(73) Assignee: **Americhip, Inc.**, Los Angeles, CA (US)

(**) Term: **14 Years**

(21) Appl. No.: **29/368,489**

(22) Filed: **Aug. 24, 2010**

Related U.S. Application Data

(63) Continuation-in-part of application No. 29/363,757, filed on Jun. 14, 2010, now Pat. No. Des. 629,458, which is a continuation-in-part of application No. 12/413,343, filed on Mar. 27, 2009, which is a continuation-in-part of application No. 12/263,277, filed on Oct. 31, 2008, which is a continuation-in-part of application No. 12/199,740, filed on Aug. 27, 2008, now abandoned.

(57) **CLAIM**

The ornamental design for a video book, as shown and described.

DESCRIPTION

FIG. 1 is a perspective view of a first embodiment of a video book showing our new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a top elevational view thereof;

FIG. 7 is a bottom elevational view thereof;

FIG. 8 is a perspective view of a second embodiment of the video book;

FIG. 9 is a top plan view thereof;

FIG. 10 is a left side elevational view thereof;

FIG. 11 is a right side elevational view thereof;

FIG. 12 is a bottom plan view thereof;

FIG. 13 is a top plan elevational view thereof;

FIG. 14 is a bottom elevational view thereof;

FIG. 15 is a perspective view of a third embodiment of the video book;

FIG. 16 is a top plan view thereof;

FIG. 17 is a left side elevational view thereof;

FIG. 18 is a right side elevational view thereof;

FIG. 19 is a bottom plan view thereof;

FIG. 20 is a top elevational view thereof; and,

FIG. 21 is a bottom elevational view thereof.

The broken line showing of portions of the video book is included for the purpose of illustrating environmental structure and forms no part of the claimed design.

1 Claim, 15 Drawing Sheets
